COMBINED TABLE AND CABINET UNIT

Constance R. Hess, 523 W. Pleasant St., Springfield, Ohio

Filed Sept. 12, 1960, Ser. No. 62,092

Term of patent 7 years

(Cl. D33—14)

Fig.1

Fig.3

FIG. 1 is a perspective view of a combined table and cabinet unit showing my new design;

FIG. 2 is a side elevational view; and

FIG. 3 is a top plan view.

The back of the cabinet portion is plain and unornamented.

I claim:

The ornamental design for a combined table and cabinet unit, as shown and described.
